UNITED STATES PATENT OFFICE

2,571,385

TREE AND LOG SAW

Isadore J. Rocklin, Sioux City, Iowa

Application September 22, 1947, Serial No. 775,414

1 Claim. (Cl. 143—68)

1

My invention relates to a tree and log saw.

An object of my invention is to provide a portable saw unit which can be transported to any desired location, and which saw unit can be used for either sawing logs on the ground, or which can be alternately used for sawing or felling trees.

A further object of my invention is to provide a unit having the above characteristics, which is powered from a small engine carried by the unit itself.

A further object of my invention is to provide in the arrangement, efficient means for providing reciprocation of the saw blade for either purpose, to provide attached means for securing the log or tree during the sawing operation, and to provide adjustable tensioning means whereby the cutting effect of the saw is adjusted to meet varying conditions.

A further object of my invention is to provide adjustable belt tensioning means and to further provide a unit wherein the parts are assembled in cooperative relation on a simple elongated carriage structure.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Figure 1 is a side elevation of the unit as it is used for cutting logs.

Figure 2 is a plan view of Figure 1.

Figure 3 is a view of the arrangement used for felling trees, and

Figure 4 is a modification.

My invention contemplates the provision of a simple unit wheeled structure having an arrangement mounted thereon for providing reciprocation to a saw blade, and wherein the arrangement can be swung and locked into position at ninety degrees from its log cutting position, so that the same arrangement can be used for felling trees.

I have used the character 10 to designate a pair of side wheels which are journaled on the transverse shaft 11, and attached at 12 is a further transverse strap 13 which is attached at 14 to a substantially long pipe 15 having the arcuate portion 16, and attached to the pipe at 17 is a gasoline engine 18 having the tank 19, the engine 18 being adapted to drive the small pulley 20.

Pivottally attached at 21 to the pipe 15 is the upwardly extending control lever 22 having the hand control member 23 which includes the engaging portion 24 for engaging the notches 25 in the arcuate ratchet member 26 which is attached to the pipe 15.

Receiving the pipe 15 is a further larger pipe 27 which includes an ear 28 attached thereto to

2

which ear is attached the rod 29 which is pivotally secured at 30 to the control lever 22. Attached at 31 to the pipe 27 is a bearing 32 which receives a short shaft 33 which is attached to the larger pulley 34.

Also attached to the pipe 27 is a support 35 which includes a bearing 36 which receives a shaft 37 which is attached to a further smaller pulley 38. Passing over the pulleys 20 and 38 is a belt 39.

Attached to the shaft 37 is a further small pulley 40 over which passes a further belt 41 which passes over the pulley 34.

Attached at 42 to the pipe 27 is a post or support 43 to which is pivotally attached at 44 to the downwardly extending arm 45 which is pivotally attached at 46 to a link 47 which is pivotally secured at 48 to any one of the openings 49 in one of the spokes of the pulley 34.

Also pivotally attached at 44 is the walking beam 50 including a hook 51 at one end adapted to engage one of the links of the chain 52 which chain 52 passes about a forward portion of the pipe member 15 at 53 and can be secured thereto.

Attached at 54 to the other end of the beam 50 is a helical spring 55 which is attached at 56 to the rod 57 which is pivotally attached at 58 to the lower end of the arm 45.

Attached at 59 to the pipe 27 are the short straps 60 which are attached to the longitudinal guide strap 61.

The pipe member 27 includes the slot 62 adapted to receive a bolt 63, the pipe 15 including a further opening at 64 for receiving the bolt when the arrangement is in the tree felling position as will be explained later.

Attached to the rod 57 at 65 is the plate 66 having an arcuate slot 67 through which slot is received the bolt 68 for fixing the saw blade in desired angular position. Attached to the plate 66 by the further bolt 69 is the saw blade 70.

Attached at 71 to the pipe 15 is a clamp 72 which extends into the upwardly projecting strap 73 which again extends downwardly into the portion 74 for providing a starting guide for the saw blade 70. Slidably engaging the pipe member 15 is a short collar 75 which is of slightly greater diameter than the pipe 15, and extending from the collar 75 is an ear 76 through which ear is secured a bolt 77, and pivotally movable about the bolt 77 is a lever 78 to which is securely attached a clevis member 79 including a slot for the reception of the chain 80. The collar 75 is attached to a downwardly extending member 81, at the lower terminal of which is attached the log penetrating point 82, and attached at 83 to the chain 80 is a further member 84 to which is attached at 85 a further pointed member 86 for penetrating into the log at the other side of the point 82.

Receiving the pipe 15 is a further larger pipe 27 which includes an ear 28 attached thereto to

A brace member 87 can be used to brace the post 43, the brace member 87 being attached to the pipe 27.

Figure 1 illustrates the use of the saw for sawing logs, and it will be noted that the pulley drive will impart rotation to the pulley 34, which correspondingly reciprocates the link 47 and the arm 45, the arm 45 being bent as shown whereby the lower portion will be guided against the member 61. This action imparts the necessary reciprocating action to the saw blade 70, and also imparts a certain amount of rocking action thereto necessary for proper cutting. The tension on the spring 55 can be adjusted by changing the attachment of one of the links of the chain 52 with the hook 51, for instance, as the saw penetrates deeper into the log, the tension can be increased in this manner by drawing upwardly on the chain 52, and in this way any desired pressure against the blade can be secured. The stroke can be adjusted by virtue of the different openings 49 and the angle of the blade 70 can also be adjusted by virtue of the bolt 68 as explained above. The unit is securely attached to the log by placing the points 82 and 86 in position and thence drawing the chain 80 up into the clevis 79, and thence throwing the lever 78 over toward the right which draws the points in together towards each other, and causing the larger diameter collar 75 to penetrate into the pipe 15 slightly due to the slight angularity of the collar with respect to the pipe 15, thereby causing a binding and firm retaining action.

The lever 22 due to its engagement with the ratchet member holds the outer pipe unit 27 in fixed position, and the lever 22 can also be used to adjust the belt tension of the belt 39 by placing the ratchet mechanism in any desired position. It will thus be seen that the unit while sawing, is in a firm and solid position to allow the full necessary action to the functioning parts.

For sawing down trees, the unit is used as shown in Figure 3 in which case the pipe 27 is rotated ninety degrees with the bolt 63 being placed through the opening 64 and in the same slot 62. The members 81 and 84, as well as the clamp 72 are also rotated in the same manner and then again secured. The lever 22 however will not be rotated to this position and will remain in the same position, however, the rod 29 which is fairly flexible will allow the pipe 27 and its assembled parts to be turned. During this use the forward end of the unit will rest upon the ground or can be blocked up slightly, and the belt 39 of course will be twisted as shown. It will thus be seen that in this position, the saw will operate as a tree felling arrangement including the same reciprocating members as well as other features.

Figure 4 illustrates a slight modification wherein a substantially U-shaped bracket 88 is attached at the top of the post 43, with a reel 89 being journaled within the bracket and including a winding handle 90 attached thereto. A pawl 91 is adapted to engage the ratchet 92, with a cable 93 being wound on the reel 89 and with the cable 93 being attached to the spring 94 which is attached at 95 to the arm 57. This structure provides an alternative arrangement for adjusting the tension of the spring 94, to provide a similar result as the spring 55 and the beam 50.

It will be noted that all of the thrusts or

strains resulting from the sawing action are absorbed between the lengthened tube 15 and the saw, so that as a result none of these thrusts are transmitted to the wheels 10 of the structure. It should also be specifically noted that the ratchet and lever member 22 provides a clutch mechanism since the ratchet can be released to draw the pulley 38 rearwardly which releases the belt 39, and in this way the power can be applied or released as desired. In this manner, the control lever acts as a clutch besides acting as means for adjustably tensioning the belt.

It will now be seen that I have provided the various advantages set forth in the objects of my invention with various other advantages being readily apparent.

Some changes may be made in the construction and arrangement of the parts of my invention without departing from the real spirit and purpose of my invention, and it is my intention to cover by my claim any modified forms of structure or use of mechanical equivalents which may be reasonably included within its scope.

I claim as my invention:

25 A saw unit comprising an elongated inner tube, a rear framework, a pair of wheels journaled to said framework, an engine attached to said framework, an outer tube receiving said inner tube, a support attached to said outer tube, an 30 arm pivotally attached to the upper end of said support, a push rod pivotally attached at the lower end of said arm, a saw blade attached to said push rod, pulleys attached to said outer tube, a link member pivotally attached to a pulley and to said 35 arm, belts engaging the pulley of said engine and said pulleys, whereby said engine will reciprocate said saw, means for securing said outer tube to said inner tube when said saw unit is used for sawing horizontally positioned logs, said outer tube 40 being rotatably mounted on said inner tube whereby said outer tube can be rotated 90 degrees with respect to said inner tube for providing means whereby said saw will function as a tree 45 felling unit, a ratchet member attached to said outer tube, a lever member pivotally attached to said ratchet member for engagement therewith, said lever member including a rod attached thereto, said rod engaging said outer tube, whereby 50 movement of said lever member will adjust the tension between said pulleys and the pulley of said engine.

ISADORE J. ROCKLIN.
